UNITED STATES PATENT OFFICE

WILLIAM D. GRANT, OF VANCOUVER, BRITISH COLUMBIA, CANADA

DRILLING EQUIPMENT

Application filed March 31, 1931. Serial No. 526,689.

This invention relates to improvements in portable and derrick drilling equipment particularly adapted for marine and subaqueous drilling.

5 The present herein-described invention is the result of long years of practical drilling experience in which many types of drilling equipment have been tested and discarded for failure to meet the exacting conditions to 10 be found in subaqueous drilling.

This experience naturally led to the development of special equipment, some of which I have been granted patents for and some being the subject matter of pending patent 15 applications, and all the apparatus so far developed has had to stand the acid test of practical application to the work in hand.

The statement above is made with the object of showing that the present invention is 20 not theoretical but a practical one tested in the field of experience.

An object of the present invention has been to develop apparatus giving a greater degree 25 of control and rigidity over the submerged drilling equipment.

Another object has been to develop stiffer and more rigid overhead equipment, as owing to the great height required in the 30 leads for carrying out subaqueous drilling, the usual timber framework has been found too resilient for this work.

Still another object of the present invention has been to develop apparatus that will 35 make possible the more accurate spotting of the casing and drill point below the overburden.

A still further object has been to provide a two-point suspension or support to the telescopic drill casing submerged below the 40 surface whereby the casing is relieved to a great extent of bending strains.

Another object has been to improve upon all known drilling equipment whereby all 45 operations are carried on with greater facility on account of the more convenient arrangement of parts and greater accessibility afforded the workmen in carrying out their duties.

All parts of the herein described invention 50 are unitary to each other to comprise an effi-

cient and effective drilling equipment suitable for subaqueous drilling, and no part can be dispensed with without rendering the remaining equipment less efficient.

A statement of the mode and sequence of 55 operation in subaqueous drilling is deemed advisable so that this invention may be thoroughly understood.

In entering upon a subaqueous drilling job it is no unusual requirement for the drilling contractor to be called upon to deepen 60 a channel or to remove an obstruction to a given survey line and this calls for accuracy in spotting the drill hole below water unless the contractor is prepared to remove a lot 65 of material he will not get paid for and even this expedient is not always permissible.

A very accurate survey of the bottom is therefore essential to successful operations, 70 first, to learn the depth of water in which operations have to be carried on; next, to learn the depth of overburden, the formation of the rock bottom, the lay of the rock, the contour of the rock in relation to the water surface, so that the depth of drilled holes may 75 be calculated for the proper estimating of cost of drilling operations and measurement of material to be removed.

Given this information the contractor then 80 prepares all his equipment to suit the particular job in hand, all drills to proper length for the deepest of holes, and these may vary from twenty to eighty feet in one length according to the depth of water in which operations are being carried out, and depth of 85 hole to be drilled. All drill bits and drill rods used are tubular.

Next in order is the telescopic casing in which the actual drilling is carried on; this 90 has to be calculated for length and run and slide to take care of rise and fall of tides if operations are in tidal waters and prepared accordingly.

All overhead hoisting cables are provided 95 to length for the handling of equipment, all ground tackle estimated for length and run to permit of the quick run-back of the drilling barge when blasting holes and thus every bit of equipment is adapted to its particular need and job.

If an under-water obstruction has to be removed to a given survey line, then sighting buoys or stations are erected, ground tackle placed accordingly and the drill barge brought in line with the drill head and drill on the sight line. The casing secured to the spud member is then lowered and forced through the over-burden by means of the spud engine; at the same time a drill is lowered within the casing and jetting operations commence by forcing a powerful stream of water through the drill rod which soon removes the over-burden and causes the casing to settle until it strikes bedrock. The bottom length of the telescopic casing is fitted with a heavy manganese shoe.

The jetting operations are continued until the casing strikes bedrock when drilling operations are commenced and the casing usually follows the drill down from six inches to two feet into the hole before becoming properly bedded and this, together with the cuttings on the outside of the casing, forms a perfect seat sufficient to maintain the high hydraulic pressures required within the casing to remove the drilling detritus.

It is to be noted that when jetting the casing down through the over-burden a considerable portion of the fine material settles back around the casing and helps to maintain a tight joint at bedrock.

With the casing accurately positioned the usual reciprocating drilling operations are carried on to depth, all detritus being hydraulically removed meanwhile from the drilled hole and through the casing.

After drilling operations are completed, the drill rod is removed by hoisting the drill head, charge lowered ready for firing, forward ground tackle slackened off, rear lines reeled and barge pulled clear to fire and then contact.

Immediately afterwards rear lines are slackened, forward lines reeled in and the barge positioned for the next hole by proper adjustment of the ground lines and operation continued.

Mobility and control are essential in such work as often there are disturbed surface conditions owing to passing vessels, also change of tides to be counteracted and quick removal of equipment for blasting operations provided for; but with the foregoing recital of the sequence of operations it is hoped to make clear a proper understanding of the various parts and functions of the present invention, which will be better understood by reference to the drawings accompanying and forming part of this application, in which:

Figure 1 is a front elevation of the barge with my invention applied.

Figure 2 is an elevation of a portion of the spud member.

Figure 2^a is a cross section of the same.

Figure 3 is another elevation of the spud member taken at right angles to Figure 2.

Figure 4 is a side elevation of the parts shown in Figure 1 and also showing the suspended loading member which, however, 70 forms no part of this invention.

Figure 5 is a cross section on the line 5—5 of Figure 4.

Figure 6 is a sectional elevation of the lower end of the casing member showing the 75 shoe.

Figure 7 is a cross section of the foot clamp which is positioned at the lower end of the spud member.

Figure 8 is a cross section showing the 80 hinged clamp member positioned upon the bow of the barge to secure the casing member.

Figure 9 is a part cross section of the leads and drilling member and a plan of the worker's platform and carriage member positioned upon the side of one of the leads.

Figure 10 is a detail side elevation of the carriage member.

Figure 11 is a detail view of the hinged 90 support on the carriage member of the platform.

Figs. 12, 13 and 14, are diagrammatic views showing the cables controlling the raising and lowering of the spud member, the drilling member and the platform, respectively.

In these drawings like numerals indicate like parts and the numeral 10 indicates a floating barge upon which is mounted a pair of metallic leads 11 supported by the trussed guy members 12. At the top of the leads 11 there is positioned a number of sheave blocks 13 to carry cables from the winding engines positioned at the after end of the barge to support and handle the various pieces of 100 drilling equipment and apparatus being used in the work in hand.

A drilling member mounted upon the face of the leads 11 is indicated at 14 and this drilling member is secured to the leads 11 by 110 the slideway 15 formed by the flat plate member 16 being riveted to the face of the leads, as shown in Figures 5 and 9. The drilling member is supported by a suitable bale 14_y secured to one of the cables 14_x 115 passing over the sheave blocks 13, and run up and down in the slideway 15 as required. The member 14 may be counterweighted as at 14_a, a cable 14_z connecting the counterweight and the member 14 and passing over one of 120 the sheave blocks 13.

The leads 11 are suitably trussed and braced by the truss bars 17 shown in Figure 4, being applied to the sides of the channel members 18 comprising the leads which are further strengthened and held apart by the bent T irons 19 as shown in Figures 1, 4, 5 and 9. A fabricated metallic spud member 20 slideable between the leads 11 is shown in position in Figures 1 and 4 extending below the bot- 130

tom of the barge 10 and is suspended by a cable 20 α passing through the sheave blocks 21 positioned on the end of the spud and over the sheave blocks 13 at the head of the leads.

5 At the bottom of the spud member 20 is positioned a foot clamp 22, a cross section of which is shown in Figure 7, and this foot clamp is for the purpose of receiving and holding in position a section of the casing 23.

10 This casing is telescopic as shown in Figures 1 and 4 and indicated at 24, and the top length of the casing is secured in the hinged clamp member 25 secured upon the bow of the barge 10 and across the well 26 formed 15 in the bow of the barge, as shown in Figures 1 and 8.

The casing 23 secured in this manner is relieved of all bending strains and is held in more rigid alignment for the operation of the 20 drilling tools therein. Moreover, the weight of the spud member upon the lower length of the casing helps to retain the casing in its original position while the barge 10 is free to rise and fall with the tide without disturbing 25 the casing setting. A heavy manganese shoe 27 is fitted to the bottom length of the casing member 23 and this is shown in Figure 6.

The hinged clamp member 25 is made removable by withdrawing drift pins fitting 30 the apertures 28 which secure the clamp member to the side brackets 29 bolted directly to the bow of the barge 10. The front half of the clamp is hingable upon the pin 30, as 35 shown in Figure 8, which also shows the apertures 28 and the side brackets 29, and the free end is secured by a threaded bolt and a wing clamp nut 31.

Positioned to the side of one of the leads 40 11 and running its whole length is an H beam 32 forming a slideway 33 for a vertical traversing carriage 34 shown in Figures 9, 10 and 11. The carriage 34 is secured to the H beam 32 by the rollers 35 carried upon the pins 36 45 secured in the framework of the carriage.

The carriage 34 has a hinge 37 formed on its outer face carrying the platform 38 which is suitably braced by the rib 39.

The platform 38 is contoured to lie around 50 in front of the leads 11 and drilling member 14 when work is to be performed thereon and is adapted to be swung clear and to the side when not required for use.

This traversing and elevating platform is 55 a great time and labour saver as it obviates the workmen running up and down the ladders found in the old style working derricks, as all that is required now is that the carriage be lowered to the deck of the barge when a 60 workman steps aboard and is hoisted immediately to the position required for attention.

The carriage has its own independent hoisting cable 34 α secured to it and passing over one of the sheaves 13 at the head of the 65 leads 11. Suitable securing means is pro-

vided for securing the end of the platform to the opposite lead when work is being carried on from the platform and to prevent it swinging when the workmen are straining upon it.

70 Figure 8 is a partial plan view of the forward deck of the drilling barge and shows the drilling well built into the bow of the barge which is indicated at 26 while the numeral 40 indicates the barge deck. For purpose of clarity the position of the leads 11 is omitted.

Having now fully described my invention, what I claim and desire to be protected in 80 by Letters Patent, is:

1. In a subaqueous drilling equipment comprising a barge and operating cables thereon in combination with a pair of vertical leads mounted upon said barge, means holding said leads in spaced apart relation, guy members supporting said leads, a slideway formed upon one face of said leads, a drilling member mounted on said slideway, and means to support said drilling member, a spud member 85 slideable between said leads, a foot clamp fitting said spud member, said foot clamp being positioned upon the lower end of said spud member and beneath the bottom of said barge. 90

2. In a subaqueous drilling equipment comprising a barge and cables thereon in combination with a pair of vertical leads and sheave blocks mounted upon said barge, said leads held in spaced apart relation by suitable members, guy members supporting said leads, a slideway formed upon one of said leads, a 95 roller carriage member slideable upon said slideway, said carriage member supporting a hinged platform member, said platform member being contoured to lie around and in front of said leads in one position and adapted to be swung to one side of said leads in another position, said carriage member and said platform member being supported in its slideway by cables, said cables passing over one of said sheave blocks to said winding engines. 100

3. In subaqueous drilling equipment, a barge, a pair of vertical leads spaced apart and mounted on said barge adjacent its bow, 105 said barge having a well, a spud member vertically slideably mounted on and between said leads to rise and fall through said well, cables and sheaves for raising and lowering said spud member, means rigidly bracing 110 said leads and holding them in spaced relation, a hinged clamp on the bow of said barge bridging the front of said well, a foot clamp on said spud member, and a telescopic casing one section of which is held by said hinged 115 clamp and the other by said foot clamp, said casing lying in front of said barge, and a drilling member vertically slideably mounted on the front of said leads above and in cooperative alignment with said casing, and 120

means to raise and lower said drilling member.

4. In subaqueous drilling equipment, a barge, vertical leads rigidly mounted and braced on said barge, a drilling member mounted on the front of said leads to be moved up and down the same, an H-beam mounted on the side of one lead, a platform carriage mounted on said H-beam, a platform carried by said carriage, sheaves mounted on said leads, and operating cables passing over said sheaves and secured to said drilling member and said carriage for raising and lowering the same.

15 5. In subaqueous drilling equipment, a barge, vertical leads rigidly mounted and braced on said barge, a drilling member mounted on the front of said leads to be moved up and down the same, an H-beam 20 mounted on the side of one lead, a platform carriage mounted on said H-beam, a platform carried by said carriage, sheaves mounted on said leads, and operating cables passing over said sheaves and secured to said drilling member and said carriage for raising and lowering the same, said platform comprising a body including a portion projected around in front of said drilling member and spaced from the leads sufficiently to permit the drilling member and platform to pass one another.

6. In subaqueous drilling equipment, a barge, a pair of fabricated leads mounted vertically on the barge and spaced apart, U-shaped brace irons embracing said leads at vertical intervals, guying means for said leads, laterally projecting vertical slideways on said leads, and a drilling member having portions embracing said projecting slideways and mounted thereon to the front of said leads, sheaves on said leads, and an operating cable passed over one of said sheaves and secured to said drilling member.

7. In subaqueous drilling equipment, a barge, a pair of fabricated leads mounted vertically on the barge and spaced apart, U-shaped brace irons embracing said leads at vertical intervals, guying means for said leads, laterally projecting vertical slideways on said leads, and a drilling member having portions embracing said projecting slideways and mounted thereon to the front of said leads, sheaves on said leads, and an operating cable passed over one of said sheaves and secured to said drilling member, a spud telescopically mounted in the space between said leads, and an operating cable passed over another of said sheaves and sustaining said spud.

60 8. In subaqueous drilling equipment, a barge, a pair of fabricated leads mounted vertically on the barge and spaced apart, U-shaped brace irons embracing said leads at vertical intervals, guying means for said leads, laterally projecting vertical slideways

on said leads, and a drilling member having portions embracing said projecting slideways and mounted thereon to the front of said leads, sheaves on said leads, and an operating cable passed over one of said sheaves and secured to said drilling member, a spud telescopically mounted in the space between said leads, and an operating cable passed over another of said sheaves and sustaining said spud, said spud having a foot clamp projecting in front of the spud, and a clamp on said barge to the front of said leads and below said drilling member, and a casing held in said clamp in cooperative position with respect to said drilling member.

In testimony whereof I affix my signature.

WILLIAM D. GRANT.
